UNITED STATES PATENT OFFICE.

AARON ACKER, OF OGDENSBURG, NEW YORK, ASSIGNOR TO THE NEWELL MFG. CO. INC.,
OF OGDENSBURG, NEW YORK, A CORPORATION OF MAINE.

SINGLE AND DOUBLE FLAT-CURTAIN-ROD BRACKET.

Application filed May 29, 1922. Serial No. 564,555.

To all whom it may concern:

Be it known that I, AARON ACKER, a citizen of the United States, residing at Ogdensburg, in the county of St. Lawrence and 5 State of New York, have invented new and useful Improvements in Single and Double Flat-Curtain-Rod Brackets, of which the following is a specification.

The present invention relates to improvements in brackets for flat curtain rods and 10 method for making the same, and has for its object to provide a bracket which may be cheaply and expeditiously produced, following my method, from suitable blanks of 15 sheet metal, with minimum waste of metal, which will give an integral rigid bracket without the necessity of assembling and securing together a plurality of parts, and which will present a bracket of pleasing appearance and one which may be readily secured 20 in place and which will permit the ready placing or removing of the curtain rods thereon, the construction further being such that when in place the rods will be held securely and rigidly in place.

Two forms of the invention are shown and described, one designed for use with a single flat curtain rod and the other for use with a plurality of curtain rods.

30 In the manufacture of articles of this kind it is essential that they be constructed at a minimum cost both as to material and labor, and that, so far as possible, waste of stock in their production be eliminated. It is desirable, for reasons of economy, that the 35 parts be as few as possible in order to eliminate the cost of assembling. The brackets must be of such construction that they may be readily attached to window casings and 40 the like, and they must be capable of sustaining, without breaking, bending or loosening from their fastenings, a reasonable weight.

In the drawings herewith I have illustrated two forms of my invention and in 45 said drawings:

Fig. 1 is a plan view of a blank from which the bracket is formed.

Fig. 2 shows the bracket in front elevation with the rod receiving finger bent into 50 final position, the rod being indicated in dotted lines.

Fig. 3 is a side elevation of the bracket shown in Figure 2.

Fig. 4 is a plan view of a blank showing 55 the double form of bracket.

Fig. 5 is a view in front elevation of the double bracket with the rod holding fingers bent to final position.

Fig. 6 is a view in side elevation of the 60 bracket shown in Figure 5.

Fig. 7 is a view in plan of the bracket shown in Figures 5 and 6 with portions of the curtain rods in position.

Referring to the drawings by numerals, 65 like numbers indicating like parts in the several views, and referring first to Fig. 1, 10 indicates the bracket blank after the first operation of stamping out and dividing the finger 11 from the body, the blank from 70 which the bracket is stamped being indicated in dotted lines. It is to be understood that this blank, indicated by dotted lines in Fig. 1, is not necessarily a single piece or unit, as it may, of course, be a portion of a large 75 sheet of stock from which the bracket blank may be struck either singly or plurally, dependent on whether a single die or a plurality of dies are used. The bracket blank 10 will be stamped out and the finger 11 80 separated from the body by the vertically disposed cut *a* with the base 12 of the finger formed by the transverse cut *b* extending inwardly substantially to the median line of the body 10 to the bending line indicated 85 by dotted lines in Fig. 1. The holes 13 may or may not be formed simultaneously with the dieing-out operation.

By this method of cutting it will be seen that there is a minimum amount of waste 90 and the single operation puts the blank into form for bending the finger into this final position. By means of the vertical and transverse cuts *a* and *b* I am able to reduce very materially the amount of metal over 95 types of brackets known to me, in which the finger supporting base, which is bent at right angles to the body to throw the finger into proper position, is formed entirely outside of the bracket body and then bent inward, as distinguished from my method of forming my base 12 entirely within the body of the bracket and then bending such base to bring the finger into proper position.

As shown in Figure 2, when the base 12 105 is bent along the dotted lines indicated in Figure 1, it forms a notch in the lower corner of the plate 10, this portion of the plate

serving, of course, to form the plate 12, the inwardly extending transverse cut *b* permitting the bending of the base inwardly so as to bring the supporting finger into substantially a central position relative to the plate 10. As will be apparent from Figure 3, this base portion 10 is a very substantial area so that it forms a strong rigid support for the finger 11.

10 By this construction, produced by following my method the brackets may be very economically produced and but little stock wasted, due to the fact that the finger supporting base is formed directly from the metal of the body of the bracket instead of being formed outside the area of the bracket and then thrown in by bending to its final position.

15 In the form of the invention shown in Figure 4 a double bracket is provided. The bracket plate 14, may, of course, take designs other than that specific design disclosed and will be struck from a blank of substantially the area shown by dotted lines.

20 As in the single form shown and described above, it will be observed that the bases 15 of the fingers are provided from the body of the bracket itself and additionally in the double form the fingers 16 are struck directly from the bracket plate 14. The plate may be died out and the fingers and bases struck at the same time, the fingers being severed from the body of the bracket along the vertical lines *c* and divided from each 25 other by the central cut *d*, while the bases 15 are separated by the transverse cuts *e* and by the single transverse cut *f*, these cuts *e* and *f* extending to the bending line indicated in dotted lines in Figure 4.

30 The bases 15 and fingers 16 thus severed may be bent outwardly to the position shown in Figs. 5 and 6, leaving the plate 14 with the centrally disposed and symmetrical aperture shown in Figure 5.

35 It will be seen that with this construction, and following my methods of making, the fingers and bases are produced entirely from the body of the bracket so that, given the outside dimensions of the bracket to be made, the 40 amount of stock necessary to produce that bracket is at once determined, for the integral base and fingers are always produced from the metal lying within the exterior dimensions of the plate.

45 This very materially reduces the amount

of metal used in forming double brackets, for it has been necessary heretofore to throw the brackets out from the exterior edges of the blank and then bend them inwardly by reverse bends to bring them into proper position within the margin of the blank.

50 Such variations in the construction and method herein disclosed as are mere variations in design or mechanical skill are, of course, to be considered as within the range of my invention.

I claim:

1. As a new article of manufacture, a curtain rod bracket having a body-portion, rod supporting fingers and finger bases, said fingers and bases being formed from a common central section of the body-portion and forced in reversed positions from the central section and lying entirely within the margin of the body-portion.

2. As a new article of manufacture, a curtain rod bracket having a body-portion, rod-supporting fingers, and finger bases; all formed of a single piece of material, and having said fingers and bases disposed in spaced relation to each other on opposite sides of a central aperture in said body portion and at an angle to said body portion.

3. The new and improved method of making curtain rod blanks, which consists in cutting a blank medially and lengthwise within its marginal edges to form a plurality of rod-supporting fingers, cutting it transversely from said medial and lengthwise cuts to form a plurality of finger bases, and bending said bases and fingers substantially along the lines of junction of said bases and blank to an angular position relative to said blank.

4. The new and improved method of making curtain brackets, which consists in cutting a blank medially and lengthwise within its marginal edges to form reversely positioned rod-supporting fingers, cutting said blank transversely from said medial and lengthwise cuts to form reversely placed finger bases, and bending said bases and fingers away from one another substantially along the line of the junction of said base and blank to an angular position relative to said blank.

In testimony whereof I have hereunto set my hand.

AARON C. ACKER.
